Primary Examiner — Selina Sikder*(74) Attorney, Agent, or Firm* — Harness, Dickey & Pierce, P.L.C.**CLAIM**

The ornamental design for a push button switch, as shown and described.

DESCRIPTION

FIG. 1 is a front elevational view of a push button switch showing a third embodiment of our new design;
 FIG. 2 is a rear elevational view thereof;
 FIG. 3 is a left side view thereof;
 FIG. 4 is a right side view thereof;
 FIG. 5 is a top plan view thereof;
 FIG. 6 is a bottom plan view thereof;
 FIG. 7 is a top, front and right side perspective view thereof, shown in separated condition;
 FIG. 8 is a bottom, rear and left side perspective view thereof, shown in separated condition;
 FIG. 9 is a front elevational view of an actuating part;
 FIG. 10 is a rear elevational view thereof;
 FIG. 11 is a left side view thereof;
 FIG. 12 is a right side view thereof; and,
 FIG. 13 is a bottom plan view thereof.
 The broken lines depict environmental subject matter only and form no part of the claimed design.
